DESIGN FOR A WINDOW SHADE BRACKET

Arthur L. Thexton, Fort Thomas, Ky., assignor to
Clopay Corporation, Cincinnati, Ohio, a corpo-
ration of Maryland

Application November 21, 1939, Serial No. 88,394

Term of patent 14 years

To all whom it may concern:

Be it known that I, Arthur L. Thexton, a citizen of the United States, residing at Fort Thomas, in the county of Campbell and State of Kentucky, have invented a new, original, and ornamental Design for a Window Shade Bracket, of which the following is a specification, reference being had to the accompanying drawing, forming part thereof.

Figure 1 is a front view of a window shade bracket showing my new design.

Figure 2 is a side view thereof.

Figure 3 is a perspective view thereof.

The characterizing feature of my design resides in the portions shown in full lines in the drawing.

I claim:

The ornamental design for a window shade bracket, as shown and described.

ARTHUR L. THEXTON.
